SEALED JOINT FOR CONCRETE SLAB
ROAD PAVEMENT

John E. Carter, Columbus, Ohio

Application May 18, 1946, Serial No. 670,791

8 Claims. (Cl. 94—18)

1

This invention relates to an improved sealed joint for concrete slab road pavement, and pertains particularly to a construction using an elastomeric and compressible joint sealing strip, cooperable with dowel bars connecting the slabs, to form a water-tight joint.

Concrete slab road construction using dowel bar coupling of the slabs to prevent tilting, requires the use of vertical joint sealing means, cooperating with the dowel bars, that is water-tight during expansion and contraction movements of the slabs due to temperature changes. Such sealing is necessary to prevent water erosion of the road bed, ice damage to the concrete, and gradual disintegration of the pavement.

Heretofore, bituminous material has been used for a sealing medium as it normally is plastic, weather resistant, and water-proof, and can be poured around the dowel bars. It is not, however, an elastomer nor is it compressible. The result is that, upon expansion of the slabs, the bituminous material is squeezed out into ridges on the surface of the road and becomes incorporated with foreign material which changes its plastic characteristics. Moreover, because it is not elastomeric, it does not return to its former shape, when the slabs contract, but leaves cracks between it and the vertical edges of the slabs, permitting water to enter. The consequence is, that the concrete of a newly laid road is almost immediately subject to weather damage which increases progressively.

Elastomeric strips, such as rubber strips, have been used instead of bituminous material, but such have been made of solid rubber, or its equivalent, which, as is well known, is elastically distortable but not compressible. That is, if it is deformed in one direction it undergoes a compensating distortion in another direction, the volume staying the same. In a compressed vertical joint, between road slabs, this distortion can only be in a vertical direction, and such a strip when subjected to squeezing, therefore, forms a ridge on the road surface subject to scuffing by traffic, which disintegrates the strip.

I have provided a novel joint sealing strip of elastomeric substance, such as natural rubber or rubber-like material, which has sealed air pockets or channels therein which permit compression of the strip without any substantial vertical distortion of it, and which is adapted to cooperate in sealed relation with elastomer covered dowel bars passing therethrough. I have combined the elastomeric characteristic of the strip with the com-

2

pressibility characteristic of an included gas to obtain my novel result.

My construction also provides easy means for assembling the strip and protected dowel bars, in the road-bed, prior to pouring concrete thereover.

The novel compressible elastomeric strip may be cut into desired lengths and sealed at the cut points to make the air pockets air-tight.

10 In use, in a slab road construction, the strip permits the necessary expansion of the slabs without any danger of water seeping into the vertical joints, and without any danger of the strip protruding above the road surface to be subjected there to the destructive scuffing of road traffic.

Therefore, the principal object of my invention is to provide an elastomeric and compressible vertical joint sealing strip for placement between concrete road slabs.

Another object of the invention is to provide such a sealing strip having sealed air pockets or channels therein.

Another object of the invention is to provide such a sealing strip with transverse holes therein for letting through dowel bars.

Another object of the invention is to provide such a sealing strip cooperable with assembly devices for maintaining the strip in place on the roadbed, before concrete is poured thereover.

Another object of the invention is to provide an elastomeric covering for the dowel bars that cooperates with the novel sealing strip to form a water-tight joint and to protect the dowel bars from water.

Further objects, and objects relating to details of construction will definitely appear from the detailed description to follow. In one instance, I have accomplished the objects of my invention 40 by the devices and means set forth in the following specification. My invention is clearly defined and pointed out in the appended claims. A structure constituting a preferred embodiment of my invention is illustrated in the accompanying 45 drawings, forming a part of this specification, in which:

Fig. 1 is a perspective view, partly in section and partly broken away, showing my invention in place in a concrete slab pavement.

50 Fig. 2 is a vertical section through Fig. 1 on the line 2—2.

Fig. 3 is a broken perspective view of my novel joint sealing strip.

55 Fig. 4 is a broken perspective view of a metal side plate used in assembling the strip to assembly chairs.

Fig. 5 is a view in perspective of an assembly chair for holding the novel strip and side plates in place.

Fig. 6 is a perspective view of a dowel bar chair.

Fig. 7 is a view of a fastener for joining two chairs such as the one shown in Fig. 6.

Fig. 8 is a modified form of a dowel bar chair.

Fig. 9 is a perspective view of a metal strip on which to seat the joint sealing strip.

Fig. 10 is a perspective view of one of the plugs fitting the open ends of the elastomeric dowel bar covering tube shown in Fig. 11.

Fig. 11 is a perspective view of a dowel bar covering tube.

Fig. 12 is a perspective view of a dowel bar.

Fig. 13 shows the sealing strip with an end closure cemented thereto, and a corner support for the strip.

Fig. 14 is a tapered wedge pin for use in retaining the strip and side plates in the chairs.

Fig. 15 shows one of the chair fastening pins.

Fig. 16 is a modified form of the strip seat of Fig. 5.

In the drawings, the same reference numerals refer to the same parts throughout the several views, and the sectional view is taken looking in the direction of the arrows at the ends of the section line.

Fig. 1 shows a perspective view of a section of pavement including a concrete pavement slab 20, an adjoining concrete slab 21, a vertical joint sealing strip 22 made of elastomeric material, dowel bars 23, 24, 25 and 26, covered with elastomeric material, piercing the strip 22 at intervals and held embedded in the concrete slabs 20 and 21. The concrete slabs 20 and 21 are cast upon a road base 27 which is in turn supported on a sub-base 28.

Prior to the casting of the concrete, the dowel bars and elastomeric strips are assembled and held in position in a rigid framework construction so that their relative positions will not be affected by the distorting forces of the concrete caused by its pressure as it is cast first on one side of a strip and then on the other side of a strip. The essential parts of this framework, as seen in Fig. 1, include a corrugated metal strip 27a positioned against one side of strip 22 with the corrugations running horizontally and a similar corrugated metal strip 28a placed against the other side of the strip in the same manner. The upper edge of each corrugated plate engages in a groove in the elastomeric strip provided for that purpose, said grooves 49 and 50 being shown best in Fig. 3. The elastomeric strip and supporting side plates rest on a metal strip 29 rimmed to the road base 27 through pinning holes 30 (Fig. 9). The elastomeric strip and supporting side plates are pierced at intervals to permit to pass through it the dowel bars 23, 24, 25 and 26 which are covered with an elastomeric casing having a snug water-tight fit. At intervals along the assembly of the elastomeric strip and side plates are chairs, such as chair 31 (see Fig. 5), having a nailing flange 32 and a toothed strip receiving slot 33. The chairs are pinned to the road base 27 through holes 34 by means of pins like pin 35. The teeth 33a in slot 33 are pointed downwardly so that any tendency of the strip and side plate assembly to move upwardly by the floating force of the concrete is thwarted. Upwardly projecting teeth 36 on the nailing flange engage the elastomeric strip's bottom edge and prevent any horizontal displacement of the strip during the pouring of the concrete. Addi-

tional bracing may be given to the strip at the ends thereof by angle plates, such as plate 37, a detail of which is shown in Fig. 13, one side of said angle plate lying against the side plate and strip and the other side of the angle plate lying along the side of one of the chairs.

Chairs are provided for the ends of the dowel bars. Chair 38, taken as an example, has a nailing flange 39, by which it is nailed to the road bed 27 by nails, such as nail 40. Each of these dowel bar chairs has two upright arms, each of which arms has therein a hole 41 (Fig. 6) for receiving an end of one of the covered dowel bars. Each of these dowel bar chairs cooperates with two of the dowel bars and, in order to form a more stable system, each dowel bar of those intermediate the outside one cooperates with two of the chairs. Thus, for instance, dowel bar 23 cooperates with chair 38 and chair 42 so that the right-hand arm of chair 38 (as seen in Fig. 1) and the left-hand arm of chair 42 both are engaged with covered dowel bar 23. Alternate chairs have their nailing flanges in the same direction but adjoining chairs have their nailing flanges pointed in the opposite direction to enable a better fit of the two adjacent chairs. Each upright arm of the chair has two stapling holes 43 (Fig. 6) which, when adjoining chairs are in place, are in alignment, so that a staple 44, such as is shown in Fig. 7, can be entered through the holes and the ears bent down to form a union of the two chairs. A modified single form of chair is shown in Fig. 8. Tapered pins, such as pin 45 (Fig. 14) may be used as a wedge between the corrugated metal side plates and the chair holding the strip in place, such tapered pins being shown in Fig. 1 at 45 and 46.

A typical pin for fastening the chairs to the road bed is shown in Fig. 15.

Referring to Fig. 3, my novel elastomeric strip is shown having a narrower lower portion 47 and a top bead portion 48 which has a concave top in cross section. The bead on either side has grooves as explained, such as groove 49 and groove 50, to receive the metal side plates. These grooves 49 and 50 are off-set vertically so that the relation between corrugations of the side plates cause the side plates to be in nesting relation against the strip when pressed tightly against it. Running lengthwise of the strip are parallel air channels, such as channel 61, which have, roughly a heart-shaped cross section. As has been explained before, the strip has dowel bar apertures 62 through which the covered dowel bars may pass.

In Fig. 4 are shown the metal side plates with the corrugations and the holes 63 which are aligned with the holes 62 of the strip with which they are placed in contact.

Referring to Fig. 13, the cut end of a sealing strip is shown sealed by a solid strip 64 of the same material cemented thereto, so that the air pockets are sealed against entry of moisture, and against the expulsion of the air when the strip is compressed. Referring to Fig. 2 there is shown a cross section of a concrete embedded dowel bar covered with an elastomeric material. The dowel bar 65 (see, also Fig. 12) is encased in a tubular vestment of elastomeric substance, the tube 66 being somewhat longer than the dowel bar so as to leave at either end empty spaces, such as spaces 67 and 67a. The tube 66 is shown in detail in Fig. 11. Stoppers or plugs are fitted in either end of the tube, one of such stoppers 68 being shown in detail in Fig. 10. Stopper 68

is shown in place in Fig. 2 in the right end of the tube, and a stopper 69 is shown in place in the left end of the tube. As has been said, the tube 66 fits snugly in aperture 62 of the strip and seals the air channels against entry of moisture. The tube covering the dowel bar protects the same against entry of water and forms an air-tight and water-tight pocket in which the dowel bar may move relatively to the concrete while still maintaining a non-tilting and load-transferring function between the slabs joined thereby.

It is, therefore, seen that the concrete slabs when expanding, under conditions met with during hot periods, exert pressure on the elastomeric strip compressing the air in the air cells without any appreciable distortion of the rubber upwardly. Any slight distortion of the rubber in a vertical direction will be taken up by the concavity along the top of the bead of the strip so that no ridge is formed above the level surface of the road.

In choosing an elastomer for use as a joint strip material and as the vestment of the dowel bar, I prefer one of the type having the characteristics of rubber or rubber-like material. Particularly, in addition to natural rubber, I prefer the use of the butadieneacrylonitrile copolymers because of their oil resistant characteristics and general good behavior under all weather conditions.

I am aware that there are available many kinds of elastomers, some of which have characteristics suitable for my purpose, and I am in no way, therefore, insisting on the use of the grease-resistant butadiene copolymer type of synthetic rubber-like material, although they are eminently suitable.

I prefer that my elastomer has a tough resilience comparable to that found in automobile tires, and one that immediately reassumes its normal shape after being distorted even by as much as 100%.

I claim that under all ordinary weather conditions my joint is far superior to any now known for waterproofing vertical joints between concrete slabs and that it will effect marked improvement in road construction by preventing water and ice damage.

It will be apparent that because the corrugated side plates normally meet the faces of the joint sealing strip at the high points of the ridges of the corrugations, there is considerable free space along the side surfaces of the strip between it and the plates, where any unusual excess of strip material, caused by distortion of the strip, may be projected, such a space 78 being shown in Fig. 2. This is a further provision against the protrusion of rubber from the vertical joints of the road above the surface level thereof and is a further feature of my invention in combination with the concave treatment of the top of the strip.

I am aware that the structures herein described are susceptible of considerable variation without departing from the spirit of my invention, and, therefore, I claim my invention broadly as indicated by the appended claims.

Having thus described my invention, what I desire to claim as new and useful is:

1. In a road construction adapted to be supported by and constructed on a road bed, in combination, a plurality of flat metal strips resting on said road bed; a plurality of internally channeled water-proof elastomeric strips standing on

edge one on each of said metal strips, the height of each of said elastomeric strips being the height of the intended pavement height, and each of said strips being slightly wider at the top edge and having slightly below its top edge on either side a downwardly opening groove flush with the narrower part of the strip and extending upwardly into the wider part of the strip; a metal side plate for each side of each of said elastomeric strips each plate extending the length of the associated strip and extending downwardly from inside of the associated groove in the strip to the associated metal strip, said side plates each being corrugated with the corrugations parallel with the road bed; means fastened into the road bed at intervals for supporting each of said elastomeric strips and associated metal side plates, in vertical position and in intimate water sealed relation with one another; a dowel bar extending through apertures in each of said elastomeric strips and associated side plates at intervals, each of said dowel bars being covered by a water-proof tube of elastomeric material sealing any of the internal channels in the elastomeric strips that are opened by the dowel apertures; plugs in each end of each of said dowel bar coverings to prevent seepage of water into the tubes and spaced from the ends of the dowel bar; means associated with the ends of the covered dowel bars for holding the same in parallel alignment a fixed distance off the road bed, said means being fastened to said road bed and to each other to form a rigid structure; and cast concrete paving sections on said road bed surrounding and covering said flat metal strips, dowel bars and dowel bar holding means, each paving section extending from the metal plate engaging one side of one elastomeric strip to the metal plate engaging an opposite side of the next adjacent elastomeric strip, and from the road bed to the level of the tops of said elastomeric strips.

2. In a jointed road pavement construction, a sealing joint assembly comprising an elastomeric sealing strip disposed edgewise in said pavement construction, said sealing strip being formed with a plurality of internal horizontally disposed channels and having a transversely enlarged upper portion, also internally channeled horizontally, forming abutments extending longitudinally along the sides of said strip near the upper edges thereof, dowel openings formed through the strip, means for sealing any of the internal channels that are opened by the dowel apertures, and a corrugated side plate adjacent one of the sides of said sealing strip and having its upper edge in engagement with one of said abutments.

3. In a jointed road pavement construction, a sealing joint assembly comprising an elastomeric sealing strip disposed edgewise in the pavement construction, said sealing strip being formed with a plurality of internal horizontally disposed sealed air channels and having a transversely enlarged upper portion, also internally channeled horizontally, forming abutments on its sides near the upper edges thereof, the abutments on opposite sides of said strip being arranged at different levels heightwise of the strip, dowel openings formed through the strip, means for sealing any of the internal channels that are opened by the dowel apertures, and corrugated side plates on the road bed adjacent opposite sides of said sealing strip and having their upper edges in engagement with and overhung by said abut-

ments with the corrugations of the respective plates arranged in nested juxtaposition.

4. In a jointed road pavement construction, a sealing joint assembly comprising a elastomeric sealing strip disposed edgewise in the pavement construction, said elastomeric strip having internally thereof sealed air channels permitting horizontal compression without substantial vertical distortion of the strip, said strip having abutments extending along the sides thereof near the upper edge, dowel apertures formed through the strip, means for sealing any of the internal channels that are opened by the dowel apertures, and corrugated side plates on the road bed adjacent opposite sides of said sealing strip and having their upper edges fitting snugly against the under side of said abutments.

5. In a jointed road pavement construction, a sealing joint assembly comprising an elastomeric sealing strip disposed edgewise in the pavement construction, said sealing strip having internally thereof horizontally disposed sealed air channels and a transversely enlarged upper portion also internally channeled, formed on either side with a downwardly opening groove flush with the narrower part of the strip and extending upwardly into the wider part near the upper edge of the strip, dowel apertures formed through the strip, means for sealing any of the internal channels that are opened by the dowel apertures, and corrugated side plates on opposite sides of said sealing strip and fitting snugly into the grooves formed in the upper portion of said strip.

6. In a jointed road pavement construction, a sealing joint assembly comprising an elastomeric sealing strip disposed edgewise in the pavement construction, said sealing strip having internal sealed air channels and a transversely enlarged upper portion, also internally channeled, formed on either side with a downwardly opening groove flush with the narrower part of the strip and extending upwardly into the wider part, the grooves on opposite sides of the strip being arranged at different levels heightwise thereof, dowel apertures formed through the strip, means for sealing any of the internal channels that are opened by the dowel apertures, and corrugated side plates on opposite sides of said sealing strip and fitting snugly within the grooves formed in the upper portion of said strip with the corrugations of said side plates arranged in nested juxtaposition.

7. In a jointed road pavement construction, a sealing joint assembly comprising an elastomeric sealing strip disposed edgewise in the pavement construction, said sealing strip being provided with an enlarged head and having internal sealed air channels permitting horizontal compression of said strip without substantial vertical distortion thereof, said strip being formed with transversely extending apertures for receiving dowel bars, corrugated side plates on opposite sides of said sealing strip formed with dowel receiving apertures and having their upper edges abutting the under side of the enlarged head of the sealing strip, dowel bars extending through said sealing strip and side plate apertures, and sealing sleeves surrounding said dowel bars and extending through said apertures to seal said apertures and the air channels in said strip opening into said apertures.

8. In a jointed road pavement construction, a sealing joint assembly comprising an elastomeric sealing strip disposed edgewise in the pavement construction, said sealing strip having internal sealed air channels permitting horizontal compression of the strip without substantial vertical distortion thereof, said strip being formed with transversely extending dowel bar receiving apertures, corrugated side plates adjacent the sides of said strip, said strip having projections extending transversely and sealing the space between the upper edges of said plates and said strip, said plates being formed with dowel bar receiving apertures aligned with the apertures in said strip, dowel bars extending transversely through said apertures, and elastomeric tubular casings surrounding said dowel bars and extending through said apertures to seal the apertures and the channels in said strip opening into said apertures.
